UNITED STATES PATENT OFFICE.

CHARLES A. SHULTZ, OF PORTLAND, OREGON.

SCOURING-CASE.

1,099,317.

Specification of Letters Patent.

Patented June 9, 1914.

Application filed March 12, 1913. Serial No. 753,869.

To all whom it may concern:

Be it known that I, CHARLES A. SHULTZ, a citizen of the United States, and a resident of the city of Portland, county of 5 Multnomah, State of Oregon, have invented a new and useful Improvement in Scouring-Cases, of which the following is a specification.

This invention relates to scouring cases 10 used in connection with grain cleaning machines.

My invention has for its object the building of a scouring case in which the abrading or scouring surfaces shall consist of a 15 mineral compound, for in my experiments such surfaces give the best results. The scouring surfaces must alternate with perforated or ventilating sections, and in order to render the construction of my scouring 20 sections convenient, it is necessary to build the case in individual units, or sections. These sections are then assembled and fastened together by means permitting the adjustment of the ventilating sections relatively to the abrading sections, so as to bring 25 their internal or working faces into true circular alinement. This feature is essential because the working faces of the ventilating sections receive relatively little wear, while 30 the scouring surfaces will be worn down in time; and, hence, in order to maintain the working faces of the alternate scouring and ventilating sections in true circular form, the construction of the case must be such as 35 to permit the relative adjustment of the ventilating sections. Such relative adjustment is effected by me by providing means whereby the ventilating sections may be readily set outward.

40 Furthermore, in my improved scouring case the individual parts are so constructed and assembled as to render and maintain the same perfectly rigid—both with respect to their unit construction and to the case 45 as a whole—when the parts are fastened together. The construction of the case in units also facilitates transportation.

The above described and incidental features embodied in my invention I attain as 50 hereinafter fully described and illustrated in the accompanying drawings.

In the latter: Figure 1 shows an end elevation, partly in section, of my scouring case; the broken lines of this figure show 55 how the ventilating sections, the internal faces of which receive very little wear, may

be moved outward radially so as to be alined with the working faces of the abrading sections, when the last mentioned faces have become worn away; Fig. 2 is a side elevation of my case with portions broken away and shown in section, so as to illustrate more clearly the interior construction of my case; Figs. 3, 4, 5 and 6 show details of construction, in isometric perspective, of the abutting end-portions of the alternate ventilating and abrading sections, which are fastened together in the building of my case, and further show such parts in the order in which they are assembled. The other details shown in these figures will be described in the body of the specification; and Fig. 7 is an end view of one of the abradant sections with the end closure-plate removed.

My case is built of alternate abrading and 75 ventilating sections, removably and adjustably fastened together. The abrading section of my case consists of a circular plate segment *e*, made of thin metal, having its lateral portions flanged as at *f*, *f*; see also 80 Fig. 3. Affixed to the longitudinal ends of this shell by rivets, *g*, are frame members, *d*, *d*, formed like flanged ring-segments. Affixed to the flanges, *f*, *f*, of the shell are longitudinal plates *c* (see Fig. 4). The latter and the ring segments, *d*, *d*, form the four sides of a pocket on the interior of the abrading section, which is filled with the abrading mineral composition *h*; and in order to give the latter a better adhering 85 surface, I have fastened open mesh wire cloth to the inner face of the cylindrical shell by rivets *j*. For the composition I prefer to use such as described in my Letters Patent of the United States dated December 90 12, 1911, No. 1,011,504.

On the exterior of the plate, *e*, is fastened one (or more) longitudinally extending reinforcing angle-iron *k*. The fastening rivets, *l*, thereof extend through the wire cloth 100 *i* and the shell *e*.

It is to be noted that the abrading section is so constructed as to be perfectly rigid, to which effect the angle-iron *k* contributes materially. Rigidity is a most important feature in this class of machinery.

The ventilating section *b* (compare Fig. 5) consists of a circular plate segment *m*, of thin metal, having its side portions formed into out-turned flanges *n*, *n*. The plate *m* 110 is provided with the usual apertures *o*, through which the impurities are withdrawn.

from the scouring chamber. The flanges, *n*, *n*, are placed in abutment with and fastened to the longitudinal plates *c*, *c*. The inner or working faces of the abrading and ventilating sections, *a*, *b*, are so curved as to form a continuous circular, cylindrical surface.

Angle-irons, *p*, *p*, (see Fig. 6) extending longitudinally on the exterior of the ventilating sections, and placed in abutment with the flanges *n*, *n*, are fastened on the exterior of the shell *m* by rivets *q*.

The flanges, *f*, *f*, of the shell, *e*, of the abrading section have bolt-holes *f'* and radial slots (*c'*, *n'*, *p'*) are provided in the longitudinal plates *c*, in the flanges, *n*, of the shell of the ventilating section, and the angle irons *p*. See Figs. 3 to 6. Bolts, *r*, passed through these slots fasten the parts 20 adjustably together.

Segmental bands, *t*, overlying the shell of the ventilating section, and fastened to the latter by the rivets *q* reinforce said shell so as to impart rigidity to this section of my 25 case.

In practice the working or abrading surface of the composition *h* will wear away evenly, and in order that the scouring chamber may be maintained in a true circular, 30 cylindrical form it will be necessary for the non-wearing surfaces, that is to say, the inner face of the ventilating section, to be occasionally alined therewith. Such adjustment is provided for in the following manner: The scouring case is stationary, while 35 the scouring cylinder revolves inside the case. In order that the case be held in constant relationship with the revolving cylinder, (of which the shaft 3 is only shown in 40 the drawings) two stationary disks 2 are inserted in the ends of the scouring case. These disks are rigidly mounted on the base 45 of the machine in connection with which the scouring case is used; the shaft 3 of the scouring cylinder extending through central holes 2^a of the disks 2.

Set-screws 4 are threaded in the segmental bands *t* and the shell of the ventilating sections *b* and bear on the disks 2. When the 50 abrading surface has been worn away, as indicated in exaggerated degree by the broken line *a'* in Fig. 1, the bolts *r* are loosened, and the set-screws 4 turned to force the ventilating section *b* outward, as indicated 55 by the broken lines *b'* of Fig. 1; in so doing bringing the working faces of the alternating sections of my case in circular alinement with each other. By then retightening the bolts *r*, the parts will again be held rigidly together.

I claim:

1. In a scouring case having alternate abrading and ventilating sections, abrading sections made of a thin circular metal plate 65 having its sides bent outward to form

radially disposed flanges, said flanges perforated for receiving bolts, heavier metal ring segments affixed transversely on the inner faces and at the ends of said plate, and closures at the sides of the circular plate, 70 said ring segments and closures forming a pocket on the inner face of the abrading section for an abradant.

2. In a scouring case having alternate abrading and ventilating sections, abrading sections made of a thin circular metal plate 75 having its sides bent outwardly to form radially disposed flanges, said flanges perforated for receiving bolts, heavier metal ring segments affixed transversely on the 80 inner faces and at the ends of said plate; and closures at the sides of the circular plate, said ring segments and closures forming a pocket on the inner face of the abrading section; and a mineral abradant filling 85 said pocket.

3. In a scouring case having alternate abrading and ventilating sections, abrading sections made of a thin circular metal plate 90 having its sides bent outwardly to form radially disposed flanges, said flanges perforated for receiving bolts, heavier metal ring segments affixed transversely on the inner faces and at the ends of said plate; closure plates at the side of said circular 95 plate, said closure plates also perforated for receiving bolts; and a mineral abradant filling in the pocket formed by said ring-segments and closure plates on the inner face of the abrading section.

4. In a scouring case having alternate abrading and ventilating sections, abrading sections made of a thin circular metal plate 105 having its sides bent outwardly to form radially disposed flanges, said flanges perforated for receiving bolts, heavier metal ring segments affixed transversely on the inner faces and at the ends of said plate, and closure plates at the side of said circular plate, said closure plates also perforated 110 for receiving bolts.

5. In a scouring case having alternate abrading and ventilating sections, each abrading section made of a thin circular metal plate having its sides bent outward 115 to form radially disposed flanges, said flanges perforated for receiving bolts, and said plate having heavier metal members fastened at its four sides forming a pocket on the inner face of said section; for an 120 abradant; and a reinforcing member affixed on the exterior of the abrading section.

6. In a scouring case having alternate abrading and ventilating sections, abrading sections made of a thin circular metal plate 125 having its sides bent outward to form radially disposed flanges, said flanges perforated for receiving bolts, and said circular plate having heavier metal members at its four sides forming a pocket on the inner 130

- face of said section; a mineral abradant filling said pocket; in combination with ventilating sections consisting of perforated circular plates having their sides 5 formed into out-turned flanges, perforated for receiving bolts; and bolts passing through said perforations of companion flanges, perforations of one of the companion flanges being elongated.
- 10 7. In a scouring case having alternate abrading and ventilating sections, abrading sections consisting of a metal shell having radially disposed flanges formed at its sides, a filling of mineral abradant in said shells, 15 ventilating sections having companion flanges formed at their sides, bolts inserted in said perforations provided in the companion flanges, disks in the ends of the scouring case, set-screws threaded through 20 the body of the ventilating section bearing on said disks, whereby the ventilating sec-

tions are adjusted, said perforations of the flanges being adapted to permit such adjustment.

8. In a scouring case having alternate 25 abrading and ventilating sections, abrading sections consisting of a metal shell having radially disposed flanges formed at its sides, a filling of mineral abradant in said shells, 30 ventilating sections having companion flanges formed at their sides, bolts inserted in said perforations provided in the companion flanges, and means for adjusting the working faces of the ventilating sections with those of the abrading sections, 35 said perforations of the flanges being adapted to permit such adjustment.

CHAS. A. SHULTZ.
